(57) **CLAIM**

The ornamental design for a simulated brick interlocking panel, as shown and described.

DESCRIPTION

FIG. 1 is a front perspective view of a simulated brick interlocking panel showing our new design;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left end elevational view thereof; and,

FIG. 8 is a right end elevational view thereof.
